(57) **CLAIM**

The ornamental design for a base for wireless charging, as shown and described.

DESCRIPTION

FIG. 1 is a top view of a base for wireless charging showing my new design;

FIG. 2 is a bottom view thereof;

FIG. 3 is a left view thereof;

FIG. 4 is a right view thereof;

FIG. 5 is a front view thereof;

FIG. 6 is a rear view thereof;

FIG. 7 is a perspective view thereof; and,

FIG. 8 is a reference view in a using state thereof.

The broken lines shown in FIG. 8 depict unclaimed environment and form no part of the claimed design.
